UNITED STATES PATENT OFFICE.

WALTER C. KAUFFMAN, OF DECATUR, INDIANA.

DESIGN FOR A COMBINED HIP-STRAP ORNAMENT AND TRACE-CARRIER.

46,744.

Specification for Design.

Patented Dec. 8, 1914.

Application filed September 8, 1914. Serial No. 860,810. Term of patent 14 years.

To all whom it may concern:

Be it known that I, WALTER C. KAUFFMAN, a citizen of the United States, residing at Decatur, in the county of Adams and State of Indiana, have invented a new, original, and ornamental Design for a Combined Hip-Strap Ornament and Trace-Carrier, of which the following is a specification, reference being had to the accompanying drawing, forming part thereof.

Figure 1 is a face view of a combined

hip strap ornament and trace carrier embodying my design. Fig. 2 is a side edge view thereof. Fig. 3 is a top plan view.

I claim:

The ornamental design for a combined hip strap ornament and trace carrier, as shown.

WALTER C. KAUFFMAN.
